(57) **CLAIM**

The ornamental design for a handstop for a firearm, as shown and described.

DESCRIPTION

FIG. 1 is a perspective view of a handstop for a firearm;

FIG. 2 is a perspective view thereof;

FIG. 3 is a rear view thereof;

FIG. 4 is a front view thereof;

FIG. 5 is a side view thereof;

FIG. 6 is a side view thereof;

FIG. 7 is a top view thereof; and,

FIG. 8 is a bottom view thereof.

The broken lines are included for the purpose of illustrating portions of the handstop for a firearm that forms no part of the claims design.

1 Claim, 8 Drawing Sheets
